US0D1103946S

(12) **United States Design Patent** (10) Patent No.: **US D1,103,946 S**
(45) Date of Patent: ** Dec. 2, 2025

(54) **CONTROLLER**

(71) Applicant: **EMOMO TECH (ZHEJIANG) CO., LTD**, Zhejiang (CN)

(72) Inventors: **Yushu Zhao**, Zhejiang (CN); **Wenji Tang**, Zhejiang (CN); **Jing Song**, Zhejiang (CN); **Wei Zhou**, Zhejiang (CN); **Jun Yang**, Zhejiang (CN); **Yi Wang**, Zhejiang (CN)

(73) Assignee: **EMOMO TECH (ZHEJIANG) CO., LTD**, Huzhou (CN)

(**) Term: **15 Years**

(21) Appl. No.: **29/967,029**

(22) Filed: **Oct. 8, 2024**

(30) **Foreign Application Priority Data**

Apr. 8, 2024 (CN) 202430188265.3

(51) LOC (15) Cl. **14-03**

(52) U.S. Cl.

USPC **D13/168**

(57) **CLAIM**

The ornamental design for a controller as shown and described.

DESCRIPTION

FIG. 1 is a perspective view of a controller showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the controller that form no part of the claimed design.

1 Claim, 8 Drawing Sheets
